UNITED STATES PATENT OFFICE.

THOMAS FRANCIS LALOR, OF OAKLAND, CALIFORNIA.

CARPENTER'S SQUARE.

1,325,097.

Specification of Letters Patent. Patented Dec. 16, 1919.

Application filed November 25, 1918. Serial No. 264,103.

To all whom it may concern:

Be it known that I, THOMAS F. LALOR, a citizen of the United States, residing at Oakland, Alameda county, California, have invented a new and useful Carpenter's Square, of which the following is a specification in such full and clear terms as will enable those skilled in the art to construct and use the same.

10 This invention relates to a carpenter's square, and its object is to provide a square which will carry upon its face all of the necessary inclination for the workman to make all the necessary cuts to produce all kinds of rafters for roofs.

An object of the invention is to provide a square which will enable the workman to instantly set off the necessary angles for roofs of nine (9) different pitches.

20 Another object of the invention is to so form the square and its operative parts as to produce all of the cuts in a given line thereby simplifying the operation of the square for the production of rafter cuts.

25 And another object of the invention is to so separate the scales as to make them easily read while at the same time they are so located as to produce all of the cuts along a single edge of the square, thereby simplifying its operation.

30 Another object of the invention is to produce a square capable of giving all of the cuts for a number of different rafters which will be of smaller size than the ordinary carpenter's square and which will dispense with the necessary calculations of a carpenter's square as used for producing rafter cuts.

35 It will be further understood by those skilled in the art that to produce rafter cuts for a number of different pitches, that with the ordinary carpenter's square the workman must have a considerable knowledge of mathematics and a considerable experience in order to be able to make the cuts for different angles and pitches of rafters, while with this invention such expert knowledge is unnecessary.

40 Other objects of the invention will appear as the description proceeds.

45 In the figures in which the same reference numeral is applied to the same portion throughout.

50 Figure 1 is a plan view of one side of the square.

55 Fig. 2 is an edge view of the square.

Fig. 3 is a plan view of the opposite side of the square.

Fig. 4 is a side elevation of the slotted guide.

Fig. 5 is an edge view of the slotted guide. 60

Fig. 6 is an end view of the slotted guide.

Fig. 7 is a side elevation of one of the bolts for securing the slotted guide to the square.

Fig. 8 is a view of the bolt shown in Fig. 65 7 looking at right angles to view shown in Fig. 7.

Fig. 9 is a plan view of the square as it appears when used simply as a square.

Fig. 10 is a plan view of the square when 70 it is used to produce cuts for octagon or hip rafters.

Fig. 11 is a plan view of the square as it is used to produce face cuts for roof boards, polygon miters and backing cuts for hip 75 rafters as well as cuts for jacks, jack rafters or valleys.

Fig. 12 shows the slotted guide secured in a position at right angles to one of the bases of the square when used as a square, both 80 bolts holding it in place.

The square consists of a flat piece of metal cut on a 45 degree angle at the corner 1 and having an arm 2 extending from the main body which main body has an opening 3 to 85 lighten the square as well as two slots 4 and 5 in which curved slots the guide holding bolts 6 and 7 are movable. The curved slots have enlargements 8 and 9 at their centers, to provide a center about which the guide 90 may move as will be later explained.

The square is also provided with holes 10 and 11 for securing the slotted guide in the position shown in Fig. 9, and it has a hole 12 for securing the slotted guide in the position shown in Fig. 10, when the cuts for octagon hip rafters are to be made. 95

The slotted guide consists of a piece of sheet metal folded to form a T-shape with legs 14 and 15 on both sides of the slot, 100 which legs are secured together at 16 and 17 by soldering or otherwise. The slotted guide is also provided with three holes 18, 19 and 20, said holes being so positioned as to permit the slotted guide to swing about the 105 several centers as much as may be necessary to produce the desired angle cuts.

Along the 45-degree side of the square is a table giving the cuts for nine different pitches of octagon hip rafters, which cuts 110

are referred to the center 12, and along this square on the same side will be found a table giving the cuts for jack rafters for hips or valleys, this table being referred to the center 9, and along the upper edge of the opening 3 will be found a table giving the nine different pitches for the backing of hip rafters. This table also refers to the center 9.

Along the bottom of the square will be found tables for bottom cuts for octagon hip or valley rafters and for common rafters, these cuts being referred to the center 8, and all of the foregoing found on Fig. 3.

In Fig. 1 there will be found a table along the 45-degree edge of the square giving the miter cuts for roof boards and the side boards for hip or valley ridge or deck rafters; these cuts are referable to the center 9. On the opposite side of this leg of the square will be found a table for miter cuts for octagon hip rafters. This table is also referable to the center 9, and along the upper side of the slot 4 will be found a table giving the face cuts for roof boards referable to the center 9.

Along the upper edge of the opening 3 is found a table giving the cuts for polygon miters referable to the center 9.

Along the base of the square will be found the plumb cuts for common rafters, hips and valleys and octagon hip rafters; these cuts are all referred to the center 8.

In operation the slotted guide is placed in a position to have its two screw bolts 6 and 7 pass through the slots 4 and 5. These two bolts each have wing nuts 22, and they have flattened portions 23 just under their heads 24 which permit said bolts to slide along the slots 4 or 5 as may be desired, or to be turned at such an angle with respect to said slots at either of the centers 8 or 9 as to cause the

guide to pivot about that center, the other bolt being used to secure the guide rigidly in any desired adjustment. In operation the guide is moved to any desired cut and rigidly secured in the position desired, whereupon the square is laid alongside of the rafter to be cut with the guide extending along the length of the rafter and the cut is at once indicated along the leg 2.

Having thus described my invention what I claim as new and desire to secure by Letters Patent of the United States, is as follows, modifications within the scope of the claims being expressly reserved:

1. In a carpenter's square a flat plate, a slotted guide, openings in said flat plate for securing the slotted guide along one side thereof and for pivoting it in several different positions, and a series of tables on the plate carrying information for producing given angles, all of said tables being referred to one edge of the plate.

2. A carpenter's square comprising a flat plate, a slotted guide adapted to be secured to said plate, the square having several holes about which said guide may be pivoted, a series of tables upon both sides of the plate for producing different angular cuts, all of said tables being referred to a single edge of the square.

3. A carpenter's square having two slots therein, each slot being concentric with an enlarged opening in the other slot, a slotted guide having openings therein, bolts for securing said slotted guide in various adjustments on the square and tables upon the square all referable to a single edge of the square for producing given angles along said edge.

THOMAS FRANCIS LALOR.
